DRAWING-OFF ARRANGEMENT OR MECHANISM FOR DEALING WITH FLEECES IN-
TERMEDIATE OF SCRIBBLERS, OR CARD-
ING ENGINESThomas Chantler, Grotton, near Oldham, Eng-
land, assignor to Platt Brothers and Company
Limited, Oldham, EnglandApplication May 29, 1942, Serial No. 445,004
In Great Britain February 3, 1942

4 Claims. (Cl. 19—150)

This invention relates to a centre drawing-off arrangement or mechanism for dealing with the fleece leaving a crushing machine for crushing burrs, skin, hard and twisted threads or fibrous material, and arranged between two scribblers or carding engines; or, alternatively, for dealing with a fleece leaving the doffer of a scribbler or carding engine and passing to another scribbler or carding engine. As is known a scribbler is a term used for a woolen carding engine and herein reference is intended to be made to woolen carding engines and waste carding engines.

In each case referred to, in the first paragraph hereof, that is, whether the fleece leaves an interposed machine for crushing burrs, etc., and passes to a succeeding carding engine; or passes from one carding engine to another; such fleece requires to be formed into a sliver for feeding or passing to a subsequent woolen or waste carding engine for further treatment.

According to the invention now to be described, the proposed centre drawing-off mechanism, for the purposes stated, comprises light sheet metal cones adapted to rotate freely, and which cones are mounted in upright position over a smooth plate or table and upon supports which are adjustable. Said cones are constructed, disposed, and mounted so as to be readily adjusted to delicately guide, and fold, the fleece by acting on the selvedges and to direct the resulting sliver to a combining trumpet mouth and driven calender rolls for the conveyance of the sliver by well known means to a subsequent carding engine.

The accompanying drawings illustrate the invention as same would be applied intermediate of a machine for crushing burrs, etc., and a succeeding carding engine, and also as applied intermediate of two carding engines.

In the said drawings:

Fig. 1 shows the improvements intermediate of a machine for crushing burrs and a succeeding carding engine (not shown) the view being a section on the line 1—1, Fig. 2.

Fig. 2 is a broken plan view at right-angles to Fig. 1.

Fig. 3 shows the improvements as they would be applied between two carding engines (the subsequent card not shown) the view being a section on the line 3—3, Fig. 4.

Fig. 4 is a broken plan view at right-angles to Fig. 3.

In the first instance there is now described the centre drawing-off arrangement or mechanism for dealing with a fleece leaving a burr crushing machine intermediate of two carding engines.

As is known in the textile trade, crushing machines for crushing burrs, etc., employ heavy or heavily weighted rollers to act upon a passing fleece and it is known to interpose such a crushing machine between two woolen or two waste carding machines according to the class of material dealt with.

In the drawings Figs. 1 and 2 a pair of burr crushing rollers of a burr crushing machine are shown and lettered B, B¹ driven in known way. Mounted in bearings carried by the framework B² of the burr crushing machine is a revolvable guide roller a and this can be driven by the gear wheels a¹, a², a³ (see Fig. 1), from the shaft of the lower burr crushing roller B¹.

There is a planished steel plate or table b which is shown mounted on support brackets or side castings b¹ secured to the framework B² of the burr crushing machine by bolts b². A forward cross-rail b³ interconnects the side castings b¹, b¹ and is secured thereto by bolts b⁴. The table b is of a proper width and advantageously somewhat longer than the length of the burr crushing rollers B, B¹.

Beneath the revolvable guide roller a and combined with the table b is a bent metal plate c which is shown as adjustable below the guide roller a, adjustment being provided for by slots c¹ and bolts c².

Over the upper face of the table b there is disposed, on each side of the longitudinal centre of the apparatus light sheet metal revolvable cones d, two being shown, on each hand, of slightly different diameter. These revolvable cones d are each shown as mounted upon a pointed spindle d¹ which engages a bush d² forced in the central support tube d³ of the cone. Each spindle d¹ is fixed to a machined bar d⁴ resting on the table b and the slot d⁵ and bolt d⁶ provide for adjustments. By such described means the relative spacing and setting of the cones d to one another, and with respect to the passing fleece F can be effected.

In connection with the table b, a trumpet mouth e is arranged. This is shown as mounted upon the cross-rail b³ in a mid-position and its lower slotted limb is shown secured to said cross-rail b³ by a screwed stud e¹. The trumpet mouth e has the known elliptical or round aperture.

Forward of said trumpet mouth e, and in a mid-position in the width of the table b calender rolls f, f¹, adapted to be driven as known, are arranged. These are shown as having their shafts mounted in slotted brackets f² secured by bolts f³ to the cross-rail b³. The devices marked

f^4 , f^5 are clearers. To effect the known driving of the calender rolls f , f^1 conventional gears, chain, and chain wheels, are shown by Fig. 1, motion being derived from the gear wheel a^1 on the shaft of the lower burr crushing roller B^1 .

With such a centre drawing-off mechanism as above described the fleece F emerging from between the burring rollers B , B^1 and passing over and supported by the roller a has its edges directed inwards by contacting with the revolable cones d , d , which are progressively more closely spaced than the distance between the ends of the burr crushing rollers. As a result, the said cones d , d direct the fleece diagonally inwards on either hand to the trumpet mouth e disposed intermediate of and forward of the cones and roll or fold or so act on the fleece to consolidate the same and produce a better blend in manner whereby the selvedges are less likely to breakdown and are better gathered into the resulting sliver which is more uniform and definite in cross-section than the slivers from other centre or side drawing arrangements. From the trumpet mouth e , the gathered fleece passes to the calender rolls f , f^1 and the sliver or end F^1 results, for conveyance to the succeeding carding engine, such conveyance of the sliver being effected by any of the well known means for such purpose.

The Figs. 3 and 4 show the second application of the centre drawing-off mechanism that is as applied between two carding engines, where no intermediate burr crushing machine is used.

In the Figs. 3 and 4 like reference letters denote similar parts to those already described and lettered in Figs. 1 and 2, and it is unnecessary to again detail same. The end structures or side castings b^1 are secured by bolts b^{2x} to the frame sides B^{2x} of the carding engine.

In this instance the fleece F^{1x} is shown as being stripped from the doffer g of the carding engine by the doffing comb g^1 and directed above the table b^x (which is shown with an upturned portion c^x) to the adjustable rotatable cones d already fully described as to their structure and manner of adjustably mounting. The cones direct and guide the fleece diagonally inwards from the sides of the apparatus. In this case, only two cones d are shown, one on either hand.

The trumpet mouth e and driven calender rollers f , f^1 are shown mounted on the cross-rail b^3 and they assist to direct the gathered fleece and produce the sliver as already described, and said sliver F^{1x} is led upwards from the calender rolls f , f^1 and conveyed by known means to a succeeding carding engine. The devices marked f^4 , f^5 are clearers. Conventional gears, chain and chain wheels are shown in Fig. 3 for driving the calender rolls f , f^1 , motion being derived from a gear wheel g^1 on the shaft of the doffer g .

It will be clear the construction and operation of the centre drawing-off mechanism is practically the same in the two arrangements described.

The features of a trumpet mouth and driven calender rolls are of course in themselves known.

I declare that what I claim is:

1. Centre drawing-off arrangement for guiding and feeding a fleece from an interposed burr crushing machine to a subsequent carding engine, comprising a table, supports therefor, pairs of light sheet-metal revolvable cones disposed in upright position on the table on either hand of the longitudinal centre of the apparatus, supporting spindles for said cones, adjustable bars carrying said spindles, means for securing adjustment of said bars, and a trumpet mouth and calender rolls forward of the table and intermediate of the cones, said cones gathering the fleece and directing same diagonally to the trumpet mouth and calender rolls to produce a single sliver for conveyance to a subsequent carding engine.

2. Centre drawing-off arrangement for guiding and feeding a fleece from one carding engine to another, comprising a table, supports for said table, light sheet-metal revolvable cones disposed in upright position on the table on either hand of the longitudinal centre of the apparatus, supporting spindles for said cones, adjustable bars carrying said spindles, means for securing adjustment of said bars, a trumpet mouth and calender rolls forward of the table and forward and intermediate of the cones, the said cones directing the fleece diagonally from either hand to the trumpet mouth and calender rolls to deliver the resulting sliver to a subsequent carding engine.

3. A centre drawing-off arrangement for guiding and feeding a fleece from a burr crushing machine to a subsequent carding engine, comprising a guide roller, means to support and drive said roller, a table, supports for said table including a cross-rail, a shaped plate and means for adjusting same, light sheet-metal cones disposed in an upright position on either hand of the longitudinal centre of the apparatus, supporting spindles for the cones, bars carrying said spindles, means to permit and secure adjustment of said bars and consequently the cones, a trumpet mouth and calender rolls intermediate and forward of the cones and carried upon said cross-rail, said cones directing the fleece in diagonal fashion inwards from each side of the apparatus, the trumpet mouth and calender rolls producing a sliver for conveyance to a subsequent carding engine.

4. A centre drawing-off arrangement for guiding and feeding a fleece from one carding engine to another carding engine, comprising a table with upturned portion, support castings for said table including a cross-rail, light sheet-metal cones disposed in an upright position on either hand of the longitudinal centre of the apparatus, supporting spindles for said cones, bars carrying said spindles, means to permit and secure adjustment of said bars and consequently the cones, said cones guiding and directing the fleece diagonally and inwards from either side of the apparatus, and a trumpet mouth and calender rolls intermediate and forward of the cones, and serving to deliver a uniform sliver for conveyance to a subsequent carding engine.

THOMAS CHANTLER.
